UNITED STATES PATENT OFFICE.

JAMES F. EVERETT, OF CHICAGO, ILLINOIS, ASSIGNOR, BY DIRECT AND MESNE ASSIGNMENTS, OF ONE-FIFTH TO BERNARD F. SCHMIDT, ONE-FIFTH TO GEORGE W. FORD, ONE-FIFTH TO CHARLES F. BURROWS, AND ONE-FIFTH TO WILLIAM T. DELIHANT, ALL OF CHICAGO, ILLINOIS.

WASHING MACHINE.

Application filed April 17, 1922. Serial No. 553,876.

To all whom it may concern:

Be it known that I, JAMES F. EVERETT, a citizen of the United States, and a resident of the city of Chicago, county of Cook, and State of Illinois, have invented certain new and useful Improvements in Washing Machines, of which the following is a specification.

My invention relates to washing machines, and has for its principal object the provision of an improved construction of this character which will be highly efficient in use, and economical in manufacture.

A further object of the invention is the provision for reversing the clothes, so that each article will be caused to rub against the adjacent article, the provision being accomplished without reversing the rotatable washing element, thereby dispensing with the expense of installing an associating reversing mechanism with the washing machine.

A further object of the invention is the provision for spreading the clothes laterally with respect to each other, upon being reversed, to create a friction or rubbing effect therebetween, and through the action of such rubbing of the clothes, the same can be washed in less time than is required in the washing machines which are now in use.

A further object of the invention is the provision of a wholly sanitary washing machine, there being no angular corners or projections for the accumulation of the washing water, dirt or the like.

Other objects will appear hereinafter.

The invention consists in the combinations and arrangements of parts hereinafter described and claimed.

The invention will be best understood by reference to the accompanying drawings forming a part of this specification, and in which,

Fig. 1 is a front elevational view of a washing machine embodying the invention,

Fig. 2 is a top plan view of the same,

Fig. 3 is a sectional detail view of the same taken substantially on line 3-3 of Fig. 1,

Fig. 4 is a fragmentary detail view of

the clothes reversing means taken substantially on line 4-4 of Fig. 3,

Fig. 5 is a sectional detail view of the same taken substantially on line 5-5 of Fig. 3, and

Fig. 6 is a fragmentary detail view of the same similar to that illustrated in Fig. 4, but showing a slightly modified form of construction.

Referring to the drawings, illustrating the preferred form of construction and which comprises a globular casing A, consisting of parts 10 and 11 having lateral flanges 12 through the medium of which 65 said parts are secured together, the casing 10 being mounted on a suitable base 13, and fixedly secured thereto, by bolts 14, said base and said casing parts being illustrated as castings, however, any other approved 70 construction will be suitable for the purpose.

Arranged within the casing A is a washing element B carrying trunnions 15 and 16 which are journalled through bearings 75 17 formed on the casing parts 10 and 11. The washing element B, which is globular in shape, is rotated through the medium of a power driven motor 18 carried by a suitable support 19 fixed to the casing part 10, 80 said washing element being operatively connected to the motor 18 by a gear 19 carried on the trunnion 15 and which meshes with a gear 20 carried on the shaft 21' of the motor 18, the ratio of the gear 85 20 to the gear 19 being about 2 to 16, and the number of revolutions per minute of the washing element is determined according to the size of the same, for reasons which will be more fully hereinafter set 90 forth.

The washing element B, as illustrated, is in the form of a casting comprising parts 21 and 22 which are spot-welded together at 23, said washing elements being perforated 95 for the admission of washing fluid to the interior thereof. Arranged in the washing element B and secured thereto by any suitable means are annular lateral ribs 24 and 25, arranged substantially at right angles to each other and which intersect at the axes of the trunnions 15 and 26.

said trunnions being extended into the interior of the washing element B and having longitudinal grooves 26 for the reception of tongues 27 formed on the opposite ends of the ribs 24 and 25. The function of the ribs 24 and 25 is such that when the washing element B is rotated, each one of the ribs in turn, will serve to force the clothes in the direction of the rotation of the 10 washing element, to the topmost position thereof, and permit the clothes to drop to the lowermost position thereof to be again forced to such topmost position by the rib which happens to be in the lowermost position. By this arrangement, as the washing element B rotates, each rib performs its individual function, through which function the clothes within the washing element are constantly reversed, said function being accomplished, as will be readily understood, without reversing the washing element, as has been heretofore the case.

As stated, the gears 19 and 20 are of a ratio 2 to 16, and the number of revolutions the washing element is capable of making depends largely upon the size of the same, this arrangement being such that the revolution of the washing element will not be too great so as to cause the clothes, by 20 centrifugal force, to continue with the rotation of the washing element. The number of revolutions of the washing element is predetermined, and in the size of a washing machine, as illustrated in the drawings, for 25 convenience sake, it might be well to mention that the washing element is capable of making approximately 39 revolutions per minute, said washing element in this instance being about 36 inches in diameter; 30 the number of revolutions and the diameter of the washing element vary according to the size desired. This number of revolutions made by the washing element will not cause the clothes to completely rotate with 35 the same, but will permit the clothes when the same reach the topmost point of the washing element, to drop to the lower position thereof, where the rib in such position, will force the clothes through a distance 40 equal to approximately one-half a complete revolution of the washing element, said lowermost and uppermost positions of said washing element being indicated for convenience sake, at 28 and 29 respectively.

50 While the function of the ribs is such that they will carry the clothes through a distance equal to approximately one-half a complete revolution of the washing element, they also serve to cause the clothes to create 55 a friction or rubbing effect between each other when the clothes drop from the position 28 to the position 29.

In addition to the clothes reversing means, I also provide additional means for 60 spreading the clothes laterally to create a

friction or rubbing effect therebetween, and to free the washing fluid held by the clothes. This means comprises a vertical rib 30, which will be hereinafter referred to as the clothes spreader, and which intersects the 70 rib members 24 and 25, at points 31. The object of the clothes spreader 30 is such that as the clothes are dropped from the position 28, the clothes will fall over and on opposite sides of the spreader, thereby being caused to spread laterally, creating a friction or rubbing effect between the clothes, spreading the clothes to such an extent as to permit the washing fluid, held therebetween, to escape. 80

The washing element B and the casing A are each provided with an opening 32 and 33 respectively, through which the clothes are discharged into the washing element, said openings being closed by doors 34 and 35 which are slidably mounted in recessed guide members 36 and 37. The doors when in closed position are locked together by a suitable latch 38, and can be provided with windows, so that one will be able to observe 90 the washing element when in operation.

Referring to the construction illustrated in Fig. 6 which is similar to that illustrated in Fig. 3 with the exception that the rib members 24 and 25 are concaved or recessed 95 on one side as at 30'. The purpose of this construction is to afford a better engaging surface for the rib members when the same come in contact with the clothes.

In operation the washing fluid is admitted into the casing A by any suitable means. The amount of washing fluid admitted into the casing A largely depends upon the proportion of clothes carried in the washing element B, said washing fluid being of a mixture which is ordinarily used in most washing machines of this type. After the clothes have been arranged in the washing element B and the proper amount of water admitted into the 100 casing A, the washing element is caused to rotate by the power-driven motor 18. The number of revolutions which the washing element is capable of making is predetermined and varies according to the size of the 105 same. As the washing element rotates, the clothes are forced from the position 29 through the medium of one of the ribs 24 and 25, to the position at 28 where the clothes, through the medium of their own 110 weight, are caused to drop down to the position 29, where they are again forced back to position 28, this operation being repeated until the clothes are properly washed. It will be noted that the clothes only travel 115 a distance equal to one-half a complete revolution of the washing element, and each time that the clothes are dropped from position 28 to position 29, the clothes are reversed, and as the same strike the spreader 120

125 130

30, the same fall on the top and opposite sides thereof, and are caused to spread laterally, creating a friction or rubbing effect therebetween. The rotation of the washing 5 element B is continued in one direction, until the clothes are properly washed, at which time the washing fluid is discharged through a discharge pipe 39 controlled by a valve 40.

By the construction of a washing machine as herein set forth, I dispense with the necessity of applying reversing mechanism for reversing the washing element of the machine. It will be observed that the ribs 10 24 and 25 are widely separated and pronounced so that as the washing element revolves these ribs form continuous elevating shelves or ledges upon which the clothes may rest and thus be carried upwardly out 15 of the washing fluid. Owing to the globular shape of the washing chamber the clothes lying on these ribs are in curved condition, the central portions thereof being farthest from the axis of rotation and the ends approaching the axis of rotation. Obviously 20 the centrifugal force varies with the distance from the axis of rotation because the peripheral speed varies with this distance. Therefore the central portions of the clothes are subjected to greater centrifugal force 25 than the side portions. The clothes are also affected by gravity, but uniformly, the central portions being affected by gravity the same as the side portions. Thus as the clothes lying upon the carrying ribs reach 30 their uppermost positions and the forward sides of the carrying ribs become vertical or substantially so, gravity first withdraws the ends of the clothes from the carrying ribs and these ends hanging downwardly in the 35 washing chamber tend to assist in withdrawing the remainder of the clothes to overcome the effect of the centrifugal force. Owing to this peculiarity in the effect of the two forces operating on the clothes, it is obvious, 40 that by means of the arrangement disclosed, the washing chamber may be operated at a relatively high speed and continuously in one direction, but nevertheless pick up the clothes and drop them from the 45 point of their greatest elevation. This has the effect of thoroughly agitating and rubbing the clothes without rolling and tangling the same into one solid mass. Thus the clothes will be thoroughly and quickly 50 cleaned and may be readily removed from the washing chamber. My improved washing machine which is globular in shape, will not only be economical in manufacture, but will be wholly sanitary, there being no angular corners or places where the washing fluid can accumulate.

While I have illustrated and described the preferred form of construction for carrying my invention into effect, this is capable of 55 variation and modification without depart-

ing from the spirit of the invention. I, therefore, do not wish to be limited to the precise details of construction set forth, but desire to avail myself of such variations and modifications as come within the scope of 70 the appended claims.

Having described my invention, what I claim as new and desire to secure by Letters Patent is:

1. A washing machine comprising a casing; a globular washing element having an open unobstructed interior and mounted to rotate on a horizontal axis in said casing; means for rotating said element constantly in one direction; and pronounced, widely 75 separated carrying ribs arranged substantially perpendicular to the direction of rotation of said washing element and having their ends located adjacent the axis of rotation and extending thence around the inner periphery of said washing element, the ends of said ribs being located comparatively close to and the central portions thereof remote from the axis of rotation, substantially 80 as described. 85

2. A washing machine comprising a casing; a globular washing element mounted to rotate in said casing; means for rotating said element constantly in one direction; and pronounced, widely separated, carrying 90 ribs extending along the inner periphery of said washing element and arranged to carry the clothes upwardly and then drop them, the forward sides of said carrying ribs being recessed, substantially 95 as described. 100

3. A washing machine comprising a casing; a globular washing element mounted to rotate in said casing; means for rotating said element constantly in one direction; pronounced, widely separated, carrying ribs 105 extending along the inner periphery of said washing element and arranged to carry the clothes upwardly and then drop them; and a central spreader rib substantially perpendicular to said carrying ribs, substantially 110 as described.

4. A washing machine comprising a casing; a globular washing element mounted to rotate in said casing; means for rotating said element constantly in one direction; pronounced, widely separated, carrying ribs 115 extending along the inner periphery of said washing element and arranged to carry the clothes upwardly and then drop them, the forward sides of said carrying ribs being recessed; and a central spreader rib substantially 120 perpendicular to said carrying ribs, substantially as described.

5. A washing machine comprising a globular casing; a washing element arranged in said casing in spaced relation with respect thereto; trunnions carried on said washing element and journaled through bearings carried by said casing; annular lateral ribs arranged in said washing element adapted to 125 130

force clothes to be washed through a half revolution of said element and then permit said clothes to drop to the bottom thereof; and an annular rib intersecting said clothes 5 forcing ribs for spreading the clothes laterally upon being dropped to the bottom of said washing element, substantially as described.

6. In a washing machine, the combination 10 with a globular casing, of a globular perforated washing element rotatably mounted in said casing; means arranged in said washing element for reversing clothes carried in said element upon the completion of every 15 half revolution thereof; and an annular lateral rib arranged in said casing for spreading said clothes on opposite sides thereof, substantially as described.

7. In a washing machine, the combination 20 with a base, of a globular casing carried by said base, said casing comprising parts fixedly secured together; a washing element arranged in said casing, there being perforations formed in the walls of said washing 25 element; means for rotating said washing element; laterally extending annular ribs arranged in said washing element substantially at right angles with respect to each other for forcing clothes carried in said 30 element through a half revolution thereof; and an annular lateral rib intersecting said clothes forcing ribs for creating the friction

or rubbing effect between the clothes at the end of said half revolution of said washing element, substantially as described. 35

8. A washing machine comprising a washing chamber substantially globular in form and mounted to rotate upon a substantially horizontal axis; ribs on the inner walls of said washing chamber arranged substantially perpendicular to the direction of rotation thereof; and a spreader rib substantially at the center of the inner wall of said chamber perpendicular to said first-mentioned ribs, substantially as described. 40 45

9. A washing machine comprising a washing chamber substantially globular in form and mounted to rotate upon a substantially horizontal axis; ribs on the inner walls of said washing chamber arranged substantially perpendicular to the direction of rotation thereof; a spreader rib substantially at the center of the inner wall of said chamber perpendicular to said first-mentioned ribs; and a casing enclosing said washing chamber, the walls of said washing chamber being foraminated, substantially as described. 50 55

In testimony whereof I have signed my name to this specification in the presence of two subscribing witnesses.

JAMES F. EVERETT.
